UNITED STATES PATENT OFFICE

106,374

DESIGN FOR A TEXTILE FABRIC

Julia Morris, New York, N. Y., assignor to Phoenix Manufacturing Co. Inc., New York, N. Y., a corporation of New York

Application June 29, 1937, Serial No. 70,110

Term of patent 3½ years

To all whom it may concern:

Be it known that I, Julia Morris, a citizen of the United States and a resident of the city of New York (Borough of Manhattan), county and State of New York, have invented the new, original, and ornamental Design for Textile Fabric, of which the following is a specification, reference being had to the accompanying drawing, forming part thereof, in which

The figure shows a piece of textile fabric embodying my ornamental design in which one repeat unit is shown.

The unit is repeated in regular succession both horizontally and vertically.

I claim:

The ornamental design for textile fabric as shown and described.

JULIA MORRIS.
